LINE LEVEL

Todd Harris, Stony Brook, N. Y.

Application October 8, 1951, Serial No. 16,873

Term of patent 14 years

(Cl. D52—1)

To all whom it may concern:

Be it known that I, Todd Harris, a citizen of the United States, residing at Stony Brook, in the county of Suffolk and State of New York, have invented a new, original, and ornamental Design for a Line Level, of which the following is a specification, reference being made to the accompanying drawing, forming a part thereof.

Figure 1 is a top plan view of a line level, showing my new design;

Figure 2 is a side view of the line level;

Figure 3 is a perspective view of the line level.

I claim:

The ornamental design for a line level, substantially as shown.

TODD HARRIS.
